A. ROOT

APPARATUS FOR AMALGAMATING

Filed April 28, 1924

UNITED STATES PATENT OFFICE.

ALEXANDER ROOT, OF SAN FRANCISCO, CALIFORNIA.

APPARATUS FOR AMALGAMATING.

Application filed April 28, 1924. Serial No. 709,540.

To all whom it may concern:

Be it known that I, ALEXANDER Root, a citizen of the United States, and a resident of San Francisco, county of San Francisco, State of California, have invented a new and useful Apparatus for Amalgamating, of which the following is a specification.

This invention relates to placer mining and has to do with apparatus for amalgamating gold and other precious metals in passing over a sluice box.

The objects of my invention are to provide a means whereby a larger percentage of the gold in placer mining may be recovered through amalgamation with mercury than hitherto accomplished, and such means which shall be simple and inexpensive to put into operation, and which may be maintained in working effectiveness at a minimum of expense.

Briefly described the method of amalgamation consists in passing the placer sand and gravel together with water over a still body of liquid mercury whereby the values are extracted by the mercury as the material is floated over the liquid surface, and my apparatus for use therewith consists in certain receptacles for the liquid mercury adapted to be placed in the bottoms of sluice boxes, mill tables, et cetera, whereby the pool of liquid mercury is presented with a proper working surface to the moving sand and gravel, means is provided to prevent splashing of the mercury by large stones, a

reservoir is provided for sinking of the amalgam, and an opening is provided in the reservoir for the removal of the amalgam without disturbing the setting of the apparatus in the sluice box; also other features are incorporated such as means for forming a tight connection between the receptacle and the bottom of the sluice box, easy renewal of the anti-splash features to provide for wear, et cetera.

In the drawings accompanying this specification Figure 1 shows in perspective the general appearance of my amalgamating receptacle; Figure 2 is a cross section of a sluice box with the receptacle in position set in an opening in the bottom of the box;

Figure 3 is an enlarged longitudinal section of the box showing the receptacle in cross section, flanged and with the flanges set into a recess in the bottom of the box; Figure 4 is an enlarged end view of one of the screen bars; Figure 5 is a plan showing a staggered arrangement of my receptacles in a mill table; and Figure 6 is a plan view of a series of the receptacles arranged in a sluice box. Figure 7 is a cross section of the receptacle showing an optional way of setting it into the bottom of the sluice box.

In its preferred form my receptacle consists of a section of pipe (1) preferably of about two inches in diameter and having an opening or slot formed in one side with an upstanding wall (2) of metal welded to the pipe all around the opening and flanged on both long edges as shown at (3). The pipe is closed or capped at both ends as shown and at one end extends a short distance beyond the wall (2) as shown at (4) so that the cap (5) will be accessible for unscrewing and so that a wrench may also be applied to the pipe to steady it if desired.

The walls (2) are preferably at a slight angle as shown more clearly in Figure 3 and form a sort of chute preferably about two inches wide on top, leading to the interior of the pipe, and transversely arranged in this chute is a number of spaced plates or grate bars (6) to form a screen over the chute opening.

Any form of grate or screen may be used over the opening but I prefer the plates as they are easily inserted in grooves (7) formed in the long walls (2) or in a separate piece attached thereto.

The bars (6) are preferably bent or twisted a trifle as denoted by the dotted lines in Figure 4, or else the opposite grooves are not quite parallel so that the plates will fit tightly into the grooves and will not float out when the receptacle is filled with mercury.

The bars or plates (6) are of iron or steel about one-sixteenth of an inch in thickness and preferably brought to a narrower edge on top as shown at (8) in Figure 4, and when all are in place they are about a half

inch apart and present a grate bar or screen surface about three-eighths of an inch below the upper edge of the chute. The receptacle is set in the bottom (9) of the sluice box as shown in Figure 3, the flanges (3) being unequally set in the wood on account of the pitch of the box, so as to present a level surface to the upper edges of the chute, and the flanges are preferably cemented and 10 screwed or bolted to the bottom of the box to make a tight joint, while the ends are similarly cemented and form a tight joint with the sides (10) of the box, and it is also desirable that the receptacle be additionally 15 supported by straps (11) passing around the pipe and bolted or lagged at (12) to the sides of the box.

Instead of setting the receptacle in the sluice box bottom as shown in Figure 3 it 20 may be done as in Figure 7 where the upper flange only is let into the wood of the box bottom and the lower flange rests on top. Other methods of applying the receptacle to the bottom of the sluice box may present 25 themselves, the important point to guard against is that the gravel should lead gently to the mercury surface so as not to violently splash into it.

In applying the receptacles to a wide box 30 or mill table several small receptacles may be used and staggered as shown in Figure 5, and in practice several of the receptacles will be placed across the sluice box in spaced 35 relation as shown in Figure 6 so as to successively treat the passing material to insure complete amalgamation of the gold.

In operation the receptacles are filled 40 with mercury to within about one-sixteenth of an inch of the upper edge, and the sand, gravel and water is run over the sluice in the usual way and when the material strikes the clear pool of mercury above the grate bars it is simply floated across by the rushing water and discharged over the far edge 45 of the chute, thus applying a bath of liquid mercury to the moving material for amalgamation of its precious metal content.

The grate bars provide a support for the 50 larger stones, thus preventing splashing of the mercury, though in case of treating reduced material or pulp the grate could be dispensed with. The upper edges of the bars are as thin as practicable to reduce the surface to which any amalgam can adhere 55 or pile up or to be carried out of the chute by the moving gravel, and being vertically arranged, permit sinking of the amalgam to the lower part of the receptacle, thus always presenting a clean surface of mercury 60 for the treating of the oncoming material. By thus treating the moving material on a pool of still mercury flouring and loss of mercury is entirely avoided and the grate bars prevent physical loss through splashing 65 from large stones, also prevent large

stones from engaging the leaving edge of the receptacle thus insuring their constant downward travel.

To remove the amalgam it is merely necessary to remove the cap (5) from the pipe 70 and take it from the open end of the pipe, and if very thick a few of the bars (6) may be removed and the amalgam pushed out from above. In this connection it is evident 75 that the grate bars (6) may be all secured together like any grate, but if separate as shown it provides for removal or changing around of those most worn.

Where a series of receptacles is used any 80 one at a time may be emptied without stopping the flow of material by simply sliding an iron cover on top of the open chute and allowing the material to pass over it until the receptacle has been emptied and re-filled with mercury. Any sand or gravel getting into the receptacle will of course float 85 out again when the receptacle is filled with mercury.

In contemplating my invention as set forth it will be seen that the one of the 90 main features is the treating of a moving body of material with a still pool of liquid mercury while preventing the mercury from 95 splashing and therefore the apparatus to carry it out may assume a variety of shapes other than the precise form shown, and any modifications thereof falling within the spirit of the invention is intended to be covered in my appended claims.

I claim:

1. Amalgamating apparatus comprising a 100 sluice box or mining table having a pool of liquid mercury in its bottom and over which the precious metal bearing deposits are adapted to pass, said pool of mercury having a retaining edge projecting above its surface, and a grate positioned below its surface substantially parallel therewith.

2. Amalgamating apparatus comprising a 110 sluice box or mining table having a pool of liquid mercury in its bottom and over which the precious metal bearing deposits are adapted to pass, said pool of mercury having a retaining edge projecting above its surface, and a series of grate bars positioned 115 just below its surface substantially parallel therewith.

3. Amalgamating apparatus comprising a 120 sluice box or mining table having a pool of liquid mercury in its bottom and over which the precious metal bearing deposits are adapted to pass, said pool of mercury having a retaining edge projecting above its surface, and a series of grate bars positioned 125 below its surface, said bars being relatively thin spaced plates placed on edge with their upper edges substantially parallel with the surface of the mercury.

4. Amalgamating apparatus comprising a 130 sluice box or mining table having a pool

of liquid mercury in its bottom and over which the precious metal bearing deposits are adapted to pass, said pool of mercury having a retaining edge projecting above its surface, and a series of grate bars positioned below its surface, said bars being relatively thin spaced plates placed on edge, and with their upper edges substantially parallel to

the surface of the mercury and being reduced in thickness.

10

5. Amalgamating apparatus comprising a pipe with an opening on the side with a wall therearound, and a grate over the opening below the edge of the wall.

ALEXANDER ROOT.
